UNITED STATES PATENT OFFICE.

ELIAS C. GLAZIER, OF ROCHESTER, NEW YORK, ASSIGNOR TO THE STEAM GAUGE AND LANTERN COMPANY, OF SAME PLACE.

TUBULAR LANTERN.

SPECIFICATION forming part of Letters Patent No. 391,240, dated October 16, 1888.

Application filed February 2, 1888. Serial No. 262,710. (No model.)

To all whom it may concern:

Be it known that I, ELIAS C. GLAZIER, of Rochester, in the county of Monroe and State of New York, have invented new and useful 5 Improvements in Tubular Lanterns, of which the following is a specification.

This invention relates to that class of lamps or lanterns which contain a tubular frame, in the lower portion of which the oil-pot and burner are supported, and in which the globe is loosely arranged, so that the globe can be raised from the burner when access is required to the latter for adjusting the wick, lighting and extinguishing the lamp, and for other 10 manipulations.

The object of my invention is to provide the lamp with a simple and convenient device for raising the globe and holding it in an elevated position.

20 The invention consists of the improvements which will be hereinafter fully described, and pointed out in the claims.

In the accompanying drawings, Figure 1 is a sectional elevation of a lamp provided with 25 my improvements. Fig. 2 is a fragmentary side elevation of the globe-lifting device on an enlarged scale. Fig. 3 is a horizontal section in line $x-x$, Fig. 1. Fig. 4 is a side elevation of a modified construction of the globe-lifting device on a reduced scale.

30 Like letters of reference refer to like parts in the several figures.

The lamp illustrated in the drawings, to which my improvements are applied, is a 35 tubular globe street-lamp, the general construction of which is well known, and which is described and shown, for instance, in Letters Patent No. 218,917, granted to Lewis F. Betts, August 26, 1879.

40 A represents the post socket at the base of the lamp-frame; B B, the air-tubes; C, the lamp-top; D, the removable air-chamber, which incloses the oil-pot d , and E the globe. The latter can be raised in the lamp-frame, so that the burner can be exposed and the air-chamber D be removed from the lamp-frame with the oil-pot and burner, if required. All of 45 these parts are old and well known.

F represents a lifting bar or frame arranged 50 on the inner side of one of the air-tubes B B, and sliding vertically in loops or eyes $f-f'$, se-

cured to the inner side of the air-tube. The lifting-bar F is provided with a hook or globe-support, G, in which the globe rests, and which is formed on or secured to an arm or lateral extension, g , formed on the lifting-bar F. The lifting-bar F is provided above the arm g with a nose or projection, g' , which engages over the upper edge of the upper loop, f , when the lifting-bar is raised, and thereby holds the latter and the globe in an elevated position, as shown in Fig. 2.

h represents a flat spring secured to the inner side of the air-tube, to which the lifting-bar is attached, and bearing with its lower 65 free end against the upper rear side of the lifting-bar, so as to force the upper portion of the latter outwardly toward the globe and retain its nose g' in engagement with the loop f . Upon pushing the lifting-bar inwardly against 70 the pressure of the spring h until the nose g' clears the upper edge of the loop f , the lifting-bar with the globe can be lowered. The upper loop, f , is made large enough to permit of the requisite lateral play of the upper portion 75 of the lifting-bar. The arm or extension g forms a stop, which prevents the lifting-bar from being raised so far as to withdraw its lower end from the lower loop, f' . A ring or loop, i , is preferably arranged on the under 80 side of the arm g , in which the thumb is inserted, and a finger-piece, i' , is secured to the outer side of the adjacent air-tube above the upper loop, f , so that the lifting-bar can be easily raised. As the lifting-bar is guided in 85 the loops $f-f'$ and the globe is attached to the lifting-bar, the globe is properly seated upon the air-chamber upon depressing the lifting-bar without any effort or attention on the part of the attendant.

90 In the modified construction of the globe-lifting device represented in Fig. 5 the spring is omitted and the locking-nose g^2 is formed on the rear side of the lifting-bar and held in engagement with the lower guide-loop by the 95 overhanging weight of the globe when the latter is raised.

I claim as my invention—

1. The combination, with the lamp or lantern frame provided with loops or guides and 100 the vertically-movable globe, of an upright lifting-bar sliding in said loops or guides and

provided with a globe-support and with a locking nose or projection which engages over one of said loops or guides and holds the lifting-bar and the globe in an elevated position, substantially as set forth.

2. The combination, with the lamp or lantern frame provided with loops or guides and the vertically-movable globe, of an upright lifting-bar sliding in said loops or guides and provided with a globe-support and with a locking nose or projection which engages over one of said loops or guides and holds the lifting-

bar and the globe in an elevated position, and a spring attached to the lamp or lantern frame bearing against the lifting-bar and holding the nose or projection thereof in engagement with the loop or guide, substantially as set forth. 15

Witness my hand this 27th day of January, 1888.

ELIAS C. GLAZIER.
